UNITED STATES PATENT OFFICE.

ALBERT BAUMGARTEN AND MATHIAS REDLINGER, JR., OF FREEPORT,
ILLINOIS.

DESIGN FOR A CONE FOR LEMON-SQUEEZERS.

SPECIFICATION forming part of Design No. 27,821, dated November 9, 1897.

Application filed June 15, 1897. Serial No. 640,924. Term of patent 14 years.

To all whom it may concern:

Be it known that we, ALBERT BAUMGARTEN and MATHIAS REDLINGER, Jr., citizens of the United States, residing at Freeport, in the county of Stephenson and State of Illinois, have invented and produced a new and original Design for the Cones or Followers of Lemon-Squeezers, of which the following is a specification, reference being had to the accompanying drawings, forming a part hereof.

In the drawings, Figure 1 is a plan view of the follower. Fig. 2 is a vertical central section of the same, and Fig. 3 is a perspective view thereof.

The leading features of our design are the truncated cone, the bur-like grooves formed in the surface of the cone, the shielding-ring about the base of the cone, the driving-knobs

on the ring, and the pocket or depression in the truncated apex of the cone.

A is the cone; A', the pocket in the truncated apex thereof; A², the concentric grooves in the surface of the cone, and A³ are transverse grooves extending from the base of the cone toward its crown, which grooves, together with the radial grooves A², impart to the cone its bur-like surface.

B is the shielding-ring, and B' are the driving-knobs thereon. 30

We claim as our invention—

The design for cones or followers for lemon-squeezers herein shown and described.

ALBERT BAUMGARTEN.
MATHIAS REDLINGER, JR.
